FASTENING PLATE FOR CONCRETE

Friedrich Karl Knohl, Roselle, Ill., assignor to Illinois Tool Works Inc., Chicago, Ill., a corporation of Delaware

Filed Mar. 5, 1969, Ser. No. 16,048

Term of patent 14 years

Int. Cl. D8—03

U.S. Cl. D8—228

FIG. 1 is a perspective view of a portion of a fastening plate for concrete, it being understood that the article has indeterminate length.

FIG. 2 is an end elevational view thereof;

FIG. 3 is a side elevational view thereof as taken along lines 3—3 of FIG. 2;

FIG. 4 is a bottom plan view thereof as taken along lines 4—4 of FIG. 2; and

FIG. 5 is a top plan view thereof as taken along lines 5—5 of FIG. 2.

I claim:

The ornamental design for a fastening plate for concrete, as shown.
